UNITED STATES PATENT OFFICE.

ABEL C. TREVIÑO, OF SAN ANTONIO, TEXAS.

GAS PRODUCER.

Application filed January 16, 1925. Serial No. 2,802.

This invention relates generally to gas producers, having more particular reference to a suction gas producer, which is intended for use in connection with an internal combustion engine the intake stroke of the piston of the engine causing the suction.

The invention has for an object the provision of a novel and improved gas producer of simple construction, and capable of ready operation in connection with an internal combustion engine.

For further comprehension of the invention, and of the objects and advantages thereof, reference will be had to the following description and accompanying drawing, and to the appended claim in which the various novel features of the invention are more particularly set forth.

Fig. 1 of the drawing is a side view of my improved gas producer.

Fig. 2 is a longitudinal vertical sectional view thereof, with parts in elevation.

Fig. 3 is a detail side elevational view showing the combination valve and door operating device.

Fig. 4 is a fragmentary plan view thereof.

Referring now to the drawing, my improved gas apparatus comprises an upright gas producer 10 having walls of refractory firebrick, and with an iron top 11 having a feed opening therein closed by a door 12. Extending downward from this opening, into the fire chamber 13, is a hopper 14 that receives the fresh coal, this hopper terminating at its lower end at a distance above the grate 15. Below the grate is an ash chamber 16 provided with a door such as indicated at 17. Connected to the ash chamber 16 is a pipe 20 that leads from an air blower 21, that may be provided with a crank handle such as 22 for manual rotation.

From the top of the fire chamber 13 is a delivery pipe 25 for the producer gas generated in the chamber, this pipe having an exhaust branch 26 thereon controlled by an ordinary valve 27. The pipe has a control valve indicated in general at 28 thereon, and may be made in two sections connected by a union 29 to permit of ready disconnection of a filter, to which the pipe leads from the gas producer.

The filter is in the form of a cylindrical casing 35, having the pipe 25 connected to its lower portion, and has extending thereacross, one near the top and one near the

bottom thereof, the screens 36 and 37 which are suitably attached to the sides of the casing. Between these two screens the casing is filled with a suitable filtering medium 38 for the gas, such as wood shavings, a suitable opening, closed by a cap 39 being provided in the top of the filter. From the top of the filter a pipe 42 joins thereafter with an air inlet branch 43, and the mixture of gas and air being led to an engine through pipe 42^a. Air pipe 43 being controlled by a hand valve 44 so that the air and gas may be mixed in desired quantities before entrance to the engine cylinders.

In the operation of my improved gas producer the hopper 14 is filled with the coal, and the latter ignited. The valves 27 and 28 being closed, and the cover or door 12 open, the air blower 21 is operated for a time to produce a draft through the bed of coal and bring the same to a state of incandescence. The operation of the blower is then reduced considerably, the valve 28 is opened, and the cover 12 closed, and the gas produced flows through the pipe 25 to the filter 35 and from the latter through the pipe 42 to an engine, not shown.

In Figs. 3 and 4 of the drawing I have shown in detail a novel means for operating the door 12 and valve 28, in a unitary manner. As here shown the door is formed on one side with a hinge ear 48 that engages between, and is hinged to a pair of hinge lugs such as 49 fixed on the top of the gas producer. This hinge element 48 has an arm extension 50 provided with a pin 51 that engages in a short longitudinal slot 52 in one end of a link 53 whose other end connects to the lower end of a lever 54 fulcrumed between its ends on a bracket 55 fixed to the pipe 25, the upper end of the lever projecting between the collars 56 fixed on the stem 28' of the valve 28 above mentioned as controlling the pipe 25. The slotted end of the link 53 is formed with a short extension 53' to which is pivotally connected one end of a short link 58 whose other end is pivotally connected to projections such as 60 from a locking bar 61 slidable on the cover or door 12 transversely of itself and guided by the straps 62 fixed on said door, this bar being adapted to engage under a pair of hooks 63 projected from the top of the producer, and thereby firmly clamp the door 12 in place.

Having thus described my invention, what

I claim as new and desire to protect by Letters Patent of the United States is as follows:

In a gas producer, in combination, a gas generating chamber with a door hingeably mounted on the top thereof, a gas outlet pipe connected to the top of said chamber, and a valve in said pipe, collars fixed to the stem of said valve, a lever fulcrumed intermediate of its ends to a stationary part, one end of said lever engaging between said collars, a link pivotally connected to the other end of said lever, the other end of said link being formed with an elongated aperture, a pin engaging said aperture and supported

from a stationary member, said link having a short extension on the end with the elongated aperture, a short link pivotally connected at one end to said short extension, a locking bar formed with projections, said projections being pivotally connected with the other end of said short link, a pair of straps fixed to said door slidably guiding said locking bar, a pair of hooks fixed to the top of said chamber, and engageable with said locking bar.

In testimony whereof I have affixed my signature.

ABEL C. TREVIÑO.
